(57) **CLAIM**

The ornamental design for a fat reducing blood bag, as shown and described.

DESCRIPTION

FIG. 1 is a perspective view of a fat reducing blood bag showing our new design;

FIG. 2 is a top plan view thereof;

FIG. 3 is a front elevation view thereof;

FIG. 4 is a right side elevational view thereof;

FIG. 5 is a left side elevational view thereof;

FIG. 6 is a rear elevational view thereof;

FIG. 7 is a bottom plan view thereof;

FIG. 8 is a perspective view of a second embodiment of a fat reducing blood bag showing my new design;

FIG. 9 is a top plan view thereof;

FIG. 10 is a front elevation view thereof;

FIG. 11 is a right side elevational view thereof;

FIG. 12 is a left side elevational view thereof;

FIG. 13 is a rear elevational view thereof; and,

FIG. 14 is a bottom plan view thereof.
